(57) **CLAIM**

The ornamental design for a portable holographic projection device, as shown and described.

DESCRIPTION

FIG. 1 is a front perspective view of a portable holographic projection device, according to an embodiment;

FIG. 2 is a front view of the portable holographic projection device illustrated in FIG. 1;

FIG. 3 is a rear view of the portable holographic projection device illustrated in FIG. 1;

FIG. 4 is a left side view of the portable holographic projection device illustrated in FIG. 1;

FIG. 5 is a right side view of the portable holographic projection device illustrated in FIG. 1;

FIG. 6 is a top view of the portable holographic projection device illustrated in FIG. 1;

FIG. 7 is a bottom view of the portable holographic projection device illustrated in FIG. 1;

FIG. 8 is a front perspective view of a portable holographic projection device, according to another embodiment;

FIG. 9 is a front view of the portable holographic projection device illustrated in FIG. 8;

FIG. 10 is a rear view of the portable holographic projection device illustrated in FIG. 8;

FIG. 11 is a left side view of the portable holographic projection device illustrated in FIG. 8;

FIG. 12 is a right side view of the portable holographic projection device illustrated in FIG. 8;

FIG. 13 is a top view of the portable holographic projection device illustrated in FIG. 8; and,

FIG. 14 is a bottom view of the portable holographic projection device illustrated in FIG. 8.

The broken lines are directed to environment and are for illustrative purposes only and form no part of the claimed design. The thin solid lines illustrate surface contour and form no part of the claimed design.

1 Claim, 14 Drawing Sheets
